UNITED STATES PATENT OFFICE.

MILES W. GARDNER, OF DETROIT, MICHIGAN, ASSIGNOR OF ONE-HALF TO
THE MICHIGAN STOVE COMPANY, OF SAME PLACE.

STOVE.

SPECIFICATION forming part of Letters Patent No. 311,653, dated February 3, 1885.

Application filed February 2, 1884. (No m^o del.)

To all whom it may concern:

Be it known that I, MILES W. GARDNER, of Detroit, in the county of Wayne and State of Michigan, have invented new and useful Improvements in Stoves; and I do hereby declare that the following is a full, clear, and exact description thereof, reference being had to the accompanying drawings, which form a part of this specification.

10 This invention relates to certain new and useful improvements in that class of stoves in which combustion takes place at the base of a column of fuel sustained and delivered by and from a magazine, and commonly called "base-burning stoves."

15 The objects of the invention are, first, to provide an effectual cut-off in the magazine that will shut off the supply of fuel in the magazine and prevent its discharge upon the 20 incandescent fuel in the fire-pot, and, second, in so constructing the magazine in sections, one sliding upon the other, that the lower end section may be raised clear from the fire below, thereby preventing any danger of burning off at the lower end, and converting a 25 base-burner into a surface-burner.

20 To this end the invention consists in the peculiar construction and arrangement of the parts forming the cut-off, and in the construction and arrangement of the magazine-sections, all as more fully hereinafter described.

30 Figure 1 is a vertical central section with cut-off open and mouth section or sleeve of the magazine lowered. Fig. 2 is a similar view 35 with cut-off closed and mouth-section of the magazine raised. Fig. 3 is a vertical section on the line X X in Fig. 2. Fig. 4 is a side elevation of Fig. 2, showing the position of the toggle-levers when the mouth-section of the 40 magazine is raised. Fig. 5 is a perspective view of the segmental plates detached. Figs. 6 and 7 are details.

45 In the accompanying drawings, which form a part of this specification, A represents the magazine proper, and is designed to be hung from the so-called middle ring of the stove or from the top, such position being determined by the style of the stove in which such magazine is to be placed.

B C represent two segmental plates, the 50 former of which is provided with the trunnions b b', which pass through proper openings in the wall of the magazine A, near the lower end, the end of the trunnion b' being squared to receive a wrench. The arms or 55 wings c of the plate C have formed in them the U-shaped openings d, which, when in place, slip over the trunnions of the plate B. A stop, e, upon the outer face of the plate C, impinging against the inner wall of the magazine, prevents such plate falling below a given point. We will now suppose that the magazine is filled with coal and the parts are in the position shown in Fig. 1. If it is desired now to cut off the supply of coal from the 60 combustion-chamber, the wrench is applied to the trunnion b'. The latter is partially rotated until the plate B is in the position shown in dotted lines in Fig. 1. At this point a lug, 65 h, upon the trunnion comes in contact with the lower side of the U-shaped arm of the plate C, when, upon giving a further turn with the wrench, the parts are compelled to assume the 70 positions shown in Fig. 2, the outer edge of the plate B resting upon a stop, i, projecting from the inner wall of the magazine proper, A. By leveling off the surface of the coal now in the fire-pot we have by the means described converted our base-burning self-feed magazine-stove into a surface-burner. Practice has 75 demonstrated that a stove provided with a cut-off of this character can be run more economically in point of fuel, a greater radiation of light and heat being had in the surface burning. It has also been demonstrated 80 that the lower end of the magazine below the cut-off from its close proximity to the incandescent fuel, where it is exposed to extreme heat, soon burns to such an extent that a new magazine must be supplied.

90 The second object of my invention is to overcome this objection; and to that end I shorten the magazine A and provide its discharge end with a vertically-adjustable sleeve-section, D, which I have arranged to operate simultaneously with the cut-off hereinbefore described. This sleeve D is slotted vertically upon opposite sides, as at k, through which slots the

trunnions b b' of the cut-off plate B project, as shown. Upon each of these trunnions I secure one end of the lever E in any convenient manner, so that it has a positive movement with the trunnions. In the opposite end of this lever I pivotally secure a lever, F, which in turn is pivoted to the sleeve D near its upper edge. It will be observed that when the sleeve is in its lowest position the levers stand relatively in the position shown in dotted lines in Fig. 1. By partially rotating the trunnions by means of a suitable wrench, as herein described, for closing the cut-off, the sleeve D is caused through the action of the levers to slide up on the magazine proper, thereby withdrawing this portion thereof from a close proximity to the fire and preventing its being burned off.

While I have described and illustrated my invention as connected to a cylindrical magazine, it is evident that it can readily be adapted to any style or shape of magazine, or that the cut-off and sleeve may be arranged to operate separately without departing from the spirit of my invention.

What I claim as my invention is—

1. The combination, with a magazine of a stove, of two segmental cut-off plates and means for partially rotating such plates in the

same direction, substantially as and for the purposes described.

2. The combination, with a magazine of a stove, of a slotted sleeve at the discharge end of such magazine, and the levers E, secured to the trunnions b b' , passing through the slots in said sleeve, and the levers F connecting said levers E with said sleeve, for vertically raising or lowering such sleeve upon the magazine, substantially as described.

3. The combination, in a magazine-stove, of an extensible magazine in two or more sections, the lower one of which can be projected or retracted, and a cut-off in the upper section of such extensible magazine, said extension and cut-off being connected to operate together, substantially as and for the purposes specified.

4. The combination, in a magazine-stove, of the magazine A and two segmental cut-off plates, B C, arranged to be partially rotated in the same direction by the operation of the trunnions common to both, substantially as set forth.

MILES W. GARDNER.
